B. W. TUTTLE, OF GALENA, ILLINOIS.

Letters Patent No. 99,374, dated February 1, 1870.

IMPROVEMENT IN WATER-WHEELS.

The Schedule referred to in these Letters Patent and making part of the same.

To all whom it may concern:

Be it known that I, B. W. TUTTLE, of Galena, in the county of Jo Daviess, and State of Illinois, have invented a new and improved Water-Wheel; and I do hereby declare that the following is a full, clear, and exact description of the construction and operation of the same, reference being had to the accompanying drawings, making a part of this specification, in which—

Figures 1 and 2 are sectional elevations, and

Figures 3 and 4 are horizontal sections through the lines x y respectively, the former, as seen, looking down upon it, and the latter looking up under it.

This invention relates to the class of turbine wheels acting on the principle of "Barker's mill;" and consists in a new and improved construction, which enables the buckets to be enlarged or contracted, at pleasure, according to the amount of available water, or the speed required; to this end,

The invention consists of three principal parts, viz:

First, the body of the wheel; secondly, the vertically-sliding gate and bucket-adjusting device; and thirdly, the annular chamber at the bottom of the wheel; said parts being all constructed and arranged to operate in connection with each other, as herein-after set forth.

In the drawings—

a a^1 a^2 represent the body of the wheel; a being a horizontal annular plate; a^1 , a circular disk, under and parallel to the plate a ; and a^2 a^3 , a series of vertical walls, connecting the plates a a^1 , and each being a kind of convolute segment, arranged as shown clearly in figs. 3 and 4.

The water, fed from above into the central opening of ring a , meets the bottom plate a^1 , and is deflected to all sides, where it forces its way out through the wall a^2 a^3 , between the several segments composing that wall, and by its reaction against such segments, turns the wheel, the openings between the segments constituting the buckets.

The object to be attained is, to enable the operator to enlarge or diminish these openings or buckets at pleasure, during the running of the wheel. This object is attained by the employment of a vertically-movable device, b b^1 b^2 , combining in itself the functions of a gate and a bucket-adjuster. Of this device, the part b is a circular horizontal plate, interposed between the plates a a^1 , and having slots to accommodate the segments a^2 . This plate is capable of being adjusted at any point between the plates a a^1 , by means described in a recent application filed by me for Letters Patent on an improvement in water-wheels, and therefore needing no further description here.

The parts b b^1 are segments of a vertical ring, attached to the outer edge of plate b , and working up

and down with it, they fitting into recesses in the perimeter of plate a^1 , as shown in fig. 3, so as to slide always in actual contact with such perimeter, thereby guiding the movement of plate b , and keeping it perfectly horizontal.

The third part, b^2 , is a radial plate, (there is a series of them, as shown by the drawings,) attached, at its upper end, to the plate b , and extending directly across each opening or bucket, as shown in figs. 1, 2, and 4.

The plates b b^1 b^2 being connected together, all are raised or lowered alike, and the size of the buckets or water-passages between segments a^2 a^3 is thus adjustable at pleasure.

Instead of making the part b b^1 b^2 movable, it might be stationary, and the part a a^1 a^2 made movable, by which precisely the same effect would be attained, it only being necessary that the parts should move with relation to each other, so as to open or close the buckets, as described.

In connection with these parts is an annular air-chamber or supporting-ring, c c^1 c^2 c^3 , consisting of two concentric rings c c^1 , connected by partitions c^2 c^3 , and provided with a floor, c^1 , and arranged beneath the other parts, as fully shown in figs. 1, 2, and 4. This not only furnishes an air-space under the other parts of the wheel, for the purposes adverted to in my former application, to which reference has already been made herein, but, at the same time, provides a suitable chamber to accommodate the gates b^2 b^3 and circular segment-walls b^1 b^1 , when the bucket-adjusting apparatus is lowered. The necessity for such a chamber will fully appear by reference to figs. 1 and 2, the former of which represents the parts b^1 b^2 as lowered into the air-chambers, the latter representing said parts as raised above the air-chambers.

The three main parts of my improved wheel may be hereafter designated by the letters A B C respectively; A including the parts represented by a a^1 a^2 , B including the parts b b^1 b^2 , and C including the parts c c^1 c^2 c^3 .

It is evident that the vertical position of these three parts might be reversed, the part C coming uppermost, and the part A nethermost, if preferred. There would be some advantage in such arrangement, in the fact that the chambers formed in part C would not be so likely to fill up with sand and gravel.

It is not indispensable that the chambers in part C should be air-chambers. On the contrary, the water may be admitted to them to any extent desired, and they may be provided with suitable openings to let it escape.

The whole wheel, as thus constructed, rotates on or with a shaft, S, of any preferred construction.

The annular ring, into which the gates slide, may,

if preferred, be made in parts, so that each gate will enter a division of its own, and the gate or slide can be examined without regard to the others.

The gates are to be raised and lowered by any suitable apparatus, that will effect the result, whether the wheel be in motion or not.

Having thus described my invention, I do not claim broadly the application of a vertically-sliding gate to a water-wheel; but

What I do claim, as my invention, is—

1. The combination of the wheel $a a^1 a^2$ with the

gate and bucket-adjuster $b b^1 b^2$, when the parts are constructed and arranged substantially as and for the purpose described.

2. The combination of the wheel $a a^1 a^2$ with the gate and bucket-adjuster $b b^1 b^2$ and annular supporting-ring $c c^1 c^2 c^3$, when the parts are constructed and arranged as and for the object specified.

B. W. TUTTLE.
